UNITED STATES PATENT OFFICE.

FREDERICK A. HART, OF NEWARK, NEW JERSEY, ASSIGNOR TO UNDERWOOD COMPUTING MACHINE COMPANY, OF NEW YORK, N. Y., A CORPORATION OF NEW YORK.

COMBINED TYPE-WRITING AND COMPUTING MACHINE.

1,214,491.

Specification of Letters Patent. Patented Jan. 30, 1917.

Application filed February 17, 1912. Serial No. 678,299.

To all whom it may concern:

Be it known that I, FREDERICK A. HART, a citizen of the United States, residing in Newark, in the county of Essex and State 5 of New Jersey, have invented certain new and useful Improvements in Combined Type-Writing and Computing Machines, of which the following is a specification.

This invention relates to the pin-setting 10 mechanism in computing machines, in which computation pins are set by the numeral keys and are then employed to limit the movements of the dial wheels or members.

15 In the combined typewriting and computing machine known as the Underwood-Hanson, a dog upon the paper carriage of the typewriter is employed for lifting one after another certain bars, each of which has a complement of computation pins; and this 20 lifting of any bar brings all the pins thereon into position to be set by the keys.

The principal object of the invention is to provide simple, inexpensive, reliable, and 25 easily operated means readily applicable to existing machines for enabling the keys to perform the function of lifting said pin bars so as to relieve the carriage from this work.

30 According to the present improvements, a universal lifter for the computation pin bars is actuated at every stroke of each numeral key; and the letter-feeding carriage of the machine determines which of said computation bars shall be lifted by the key; or in other words, said carriage selects the denomination of the computation pin which is to be set by any key at any point in the column of figures.

40 There is employed the usual dog upon the carriage which operates *seriatim* the usual denominational jacks upon the machine frame; and links connect these jacks to a nest of linkages, whereby the order of 45 operation is reversed, so that when the extreme right-hand jack is displaced by said carriage dog, the extreme left-hand linkage is actuated. Each of these linkages is adapted to effect a connection between its associated computation-pin bar and said universal lifter, so that the operation of the latter (which occurs during the key stroke) causes the selected pin-bar to be elevated, and

hence the key which is being depressed may set a pin on said elevated bar. 55

Other features and advantages will hereinafter appear.

In the accompanying drawings, Figure 1 is a sectional elevation from front to rear of an Underwood-Hanson combined type-writing and computing machine, embodying the present improvements. Fig. 2 is a plan of the carriage dog and the computation jacks operable thereby. Fig. 3 is a view similar to the lower portion of Fig. 1, 60 but showing a numeral key depressed. Fig. 4 is a rear elevation of a nest of transposition linkages. Fig. 5 is a perspective view of one of the linkages seen at Fig. 4, and the device whereby it connects its associated 65 computation-pin bar with the universal lifter for the pin bars. 70

Alphabet keys 1 and numeral keys 2, provided upon the forward ends of levers 3, are operated to rock bell cranks 4 to swing 75 type bars 5 up against a platen 6. The platen is mounted upon a carriage 7, which is propelled by a spring barrel 8 and controlled in the usual manner by an escape- 80 ment wheel 9 and dogs 10; the latter operated by a universal bar 11, which is driven by heels 12 on the type bars. Dial wheels 13 are operated by pinions 14, which mesh with racks 15 formed upon bars 16, one bar 85 for each dial wheel; each bar carrying a set of computation pins 17, which are depressible by linkages 18, the latter including rock shafts 19 which have the usual arms 20 engageable by stems 21 pendent from the 90 numeral keys 2. The depression of any numeral key 2 to operate its type bar causes the depression of the corresponding linkage 18, whereby one of the pins 17 is depressed in the path of a bar 22 on a general operator 23, which is operated by a crank 95 24 after all of the desired pins 17 have been set. The crank is fixed upon a rock shaft 25; and the shaft carries a gear 26, which meshes with an idle pinion 27, the latter meshing with the rack 23 and forming part 100 of the general operator for the computing wheels. The pins 17 therefore form part of an indexing mechanism which determines how far the general operator will drive the computing wheels. 105

In order to depress or set one of the pins

17, however, its bar 16 must be lifted above the other bars; and this is done by a denomination-selecting mechanism, which is controlled by the typewriter carriage 7 in conjunction with the numeral keys 2.

Upon the stem 21 of each numeral key 2 is carried a pawl 28; and in the paths of these pawls or projections a horizontal universal bar 29 extends across the machine, so as to be depressed upon the down stroke of any numeral key 2. This universal bar is mounted upon arms 30 at opposite sides of the machine, said arms pivoted to the framework at 31 between the ends of the latter. Joining the rear ends of the arms 30 is a second universal bar 32, which rises when the universal bar 29 is depressed; and by means of said bar 32 any one of a series of floating interponents in the form of hooks 33 may be lifted, to raise the rear end of its associated pin-carrying bar 16. There is one hook 33 for each of said bars 16; and they are mounted upon a transverse fixed rod 34. It will be noted that hooks 33 in addition to having a pivotal connection with the rod 34, also have slots 33' whereby the hooks may be moved vertically relative to the bar 34 to raise the corresponding pin bars 16.

20 Normally the hooks 33 are all held out of working positions by individual tension springs 35; but as the paper carriage 7 of the typewriter progresses, the hooks 33 are swung forwardly one after another to catch 25 under the computation bars 16; these movements of the hooks being effected by linkages, each comprising a vertical link or bar 36 having a projection 37 to engage the hook and throw it beneath the adjacent bar 40 16. At each such motion of the hook about the pivot rod 34, a catch 38 thereon swings over the universal bar 32, so that at the depression of the key 2, the hook 33 is carried up by said universal bar 32, thus lifting 45 the associated bar 16, so that the pins 17 thereon are above the other pins in the nest, and so that the descending linkage 18 will depress or set one of the pins on said elevated bar. The work of lifting the bar 50 and depressing the pins is all taken by the finger key, thus relieving the paper carriage of work, and making it lighter to run and more sensitive and speedy in operation. Upon the relief of the key from pressure, it 55 is returned to position by the usual spring 39. The universal bar frame 30 is returned by a spring 40, and hook 33 returns to normal position under the influence of spring 35, thus permitting the computation bar 16 to drop. The hooks 33 also have springs 41 to pull them down to normal positions after actuation. The linkages comprising the bars 36 are returned by springs 42. The movements of the linkages 36 are effected by a 60 dog 43 carried by an arm 44 on the carriage

7, said dog lifting the forward ends of a series of jacks 45 one after another; said jacks pivoted on a fixed rod 46 and the rear ends operating to depress links 47 whose lower ends are pivoted to cranks 48 on horizontal rock shafts 49. Each of these rock shafts 49 carries a crank 50 to engage a pin 51 in a link 52, which connects arms 53 and 54 of a pair of bell cranks. These bell cranks also comprise arms 55, 56, which are pivotally connected by the bars or links 36 70 75

At each motion of the paper carriage, in the computing zone thereof, one of the jacks 45 is operated, and the corresponding link 47 is thrust down and the rock shaft 49 is rocked, and linkages 52, 53, 55 and 36 are operated to thrust forwardly the hook 33 beneath the associated computation rack 16.

It will be seen at Fig. 4, which is a rear elevation, that the linkages 53, etc., form a transposition device, whereby the first operated jack 45 is connected to the computation bar 16 of highest denomination, the second jack to the bar of next lower denomination, and so on.

As, in some cases, the carriage 7 may move so promptly and with such speed as to cause one of the hooks 33 to be swung about the pivot rod 34, while the universal bar 32 is still elevated, provision is preferably made for pivoting the latches 38 at 57, to the upper arm 58 of the hook 33, so that the said universal bar 32 may swing any interfering latches one side and descend notwithstanding that another hook 33 is pressed forwardly by the projection 37. A spring 59 will snap the latch 38 over the universal bar 58 when the latter returns to normal position. 105

Variations may be resorted to within the scope of the invention, and portions of the improvements may be used without others. 105

Having thus described my invention, I claim:

1. The combination with a typewriting mechanism having a carriage, of computing mechanism having a series of dial wheels and a bar operating each dial wheel, means individual to each bar and normally out of contact therewith for moving it away from its fellows, and carriage controlled means for bringing said individual means separately into engagement with the associated key-controlled bars. 110
115

2. The combination with a typewriting mechanism having a carriage, of computing mechanism having a series of dial wheels and a bar operating each dial wheel, means individual to each bar and normally out of contact therewith for moving it away from its fellows, carriage controlled means for bringing said individual means separately into engagement with the associated bars, and mechanism universal to all of said individual means for actuating said individual means 120 125 130

vidual means to manipulate said key-controlled bars.

3. The combination with a typewriting mechanism having a carriage, of computing mechanism having a series of dial wheels and a bar operating each dial wheel, means individual to each bar and normally out of contact therewith for moving it away from its fellows, carriage controlled means for bringing said individual means separately into engagement with the associated bars, mechanism universal to all of said individual means for actuating said individual means to actuate said bars, said typewriting mechanism having numeral keys, and connections between said numeral keys and said universal mechanism enabling said keys to actuate said universal mechanism to actuate said bars.

20 4. The combination with a typewriting mechanism including a carriage and numeral keys, of a computing mechanism including a series of dial wheels and bars for operating the dial wheels, said bars shiftable by said keys, means carried by said carriage for determining the individual operation of said bars, transposition linkages between said bars and said means, said transposition linkages being normally dis-

30 connected from said bars, and interponent mechanism between said transposition linkages and said bars, for completing the connection between said means and said bars.

5. The combination with a typewriting mechanism including a carriage and numeral keys, of computing mechanism including a series of dial wheels and bars for operating said dial wheels, carriage controlled means for selecting the individual bars to be operated, linkages extending between said means and said bars, said linkages being normally disconnected from said bars, interponent mechanism individual to each of said bars and each of said linkages for effecting a completion of the connection between said means and said bars, and numeral key actuated means for operating said interponent mechanism.

6. The combination with a typewriting mechanism including a carriage and numeral keys, of computing mechanism including a series of dial wheels, and bars for actuating said dial wheels, carriage controlled means for determining the bar to be actuated in concomitance with the actuation of a numeral key, linkages extending from said means to said bars, but normally out of connection therewith, interponent mechanism for effecting the completion of connection between said linkages and said bars, and means universal to said keys and connectible to said interponent mechanism whereby said keys may be caused to actuate said bars.

65 7. The combination with a typewriting

mechanism, of a computing mechanism having a series of dial wheels and bars for actuating said dial wheels, a series of hooks individual to said bars and normally out of engagement therewith, linkages for operating said hooks operated in turn by certain parts of said typewriting mechanism, and means for raising all of said hooks.

8. The combination with a typewriting mechanism including numeral keys, of computing mechanism having a series of dial wheels and bars for operating said dial wheels, a series of hooks individual to said bars and normally out of contact therewith, a bar universal to said keys and operated thereby, a bar universal to said hooks and operated by said first-mentioned universal bar, and means operated by certain parts of said typewriting mechanism other than said keys, for determining which of said hooks shall be in connection with its associated bar at any particular instant.

9. The combination with a typewriting mechanism, of a computing mechanism including a series of dial wheels, and bars individual to each dial wheel for operating the same, a series of hooks pivotally and slidably mounted, and normally out of contact with said bars for operating said bars, means actuated by certain parts of said typewriting mechanism for determining which of said hooks shall come into engagement at any particular instant with the associated bar, and means for shifting all of said hooks.

10. The combination with a typewriting mechanism having a carriage, of computing mechanism including a series of dial wheels and a bar for each wheel, a dog movable concomitantly with said carriage, a series of jacks operable by said dog, linkages operated by said jacks for enabling the operation of said bars, and means individual to said bars for moving said bars normally disconnected from said bars, and brought into engagement therewith *seriatim* by said linkages as said dog moves successively into engagement with said jacks.

11. The combination with a typewriting mechanism, of a computing mechanism including a series of dial wheels and bars for operating said dial wheels, a series of hooks individual to each of said bars and normally out of engagement therewith, said hooks being slidably and pivotally mounted, means individual to said hooks for individually swinging said hooks into engagement with the associated bars, and means universal to said hooks for sliding said hooks to move the bar with which the associated hook is in engagement.

12. The combination with a typewriting mechanism, of a computing mechanism including a series of dial wheels and bars for operating said dial wheels, hooks individual

- to said bars, and normally out of contact with said bars, means actuated by certain parts of said typewriting mechanism for shifting the said hooks individually into engagement with the associated bars, a bar universal to said hooks, and spring pressed means on said hooks adapted to engage said universal bar.
13. The combination with a typewriting mechanism including a series of numeral keys, of a computing mechanism including a series of dial wheels and bars for operating said dial wheels, hooks individual to said bars, and connections between said numeral keys and said hooks whereby said hooks may be actuated by said numeral keys.
14. The combination with a typewriting mechanism including numeral keys, of a computing mechanism including dial wheels, bars having pins thereon for operating said dial wheels, linkages for setting said pins, hooks individual to said bars for moving said bars individually away from their fellows, numeral key operated means for actuating said linkages, and numeral key operated means for actuating said hooks.
15. The combination with a typewriting mechanism including numeral keys, of a computing mechanism including dial wheels, bars having pins for actuating said dial wheels, linkages for setting the pins on said bars, hooks individual to said bars for lifting said bars separately away from their fellows, said hooks being slidably mounted, a spring pressed latch mounted on each of said hooks, numeral key operated means engaging said latches, to lift said hooks and thereby lift said bars, and key operated means for shifting said linkages to set an accordant pin on the lifted bar.
16. The combination with a typewriting mechanism including numeral keys, of a computing mechanism including a series of dial wheels, bars for actuating said dial wheels having settable pins thereon, linkages operated by said numeral keys for engaging said pins when said bars are raised, hooks individual to said bars for raising said bars, a bar universal to said hooks for lifting said hooks, and a bar universal to said keys for operating said first-mentioned universal bar.
17. The combination with a typewriting mechanism including a plurality of numeral keys, of a computing mechanism including a plurality of dial wheels, a series of bars individual to said dial wheels for operating the same, each of said bars having a series of settable pins thereon, linkages for setting said pins, stems carried by said keys for operating said linkages and said bars, hooks individual to said bars for raising said bars, a universal bar adapted to raise said hooks, a universal bar connected to said first-mentioned universal bar, and pawls individual to said numeral keys for actuating said second-mentioned universal bar concomitantly with the actuation of said linkages.
18. The combination with a typewriting mechanism including numeral keys, of a computing mechanism including a series of dial wheels and bars for actuating said dial wheels, a series of hooks individual to said bars, spring means for normally holding said hooks out of engagement with said bars, parallel linkages, operable by certain parts of said typewriter mechanism, individual to each of said hooks, and capable of shifting said hooks individually into engagement with the associated bar, and numeral key operated means for shifting said bars when said hooks are in engagement therewith.
19. The combination with a typewriting mechanism, of a computing mechanism including a series of dial wheels and a series of bars individual to said dial wheels and adapted to operate the same, a series of hooks individual to said bars and normally out of engagement therewith, parallel linkages individual to said hooks and adapted to force said hooks into engagement with the associated bars, bell cranks individual to said linkages for operating the same, a link connected to each of said bell cranks, a series of jacks individual to said links for operating the same, and typewriting mechanism controlled means for successively vibrating said jacks.
20. The combination with a typewriter mechanism including a carriage, of a computing mechanism including a series of dial wheels and bars individual to said dial wheels for operating the same, a series of hooks individual to each of said bars and normally out of contact therewith, parallel linkages associated with each of said hooks for forcing said hooks into engagement with said bars, a bell crank for operating each of said linkages, a link connected to each of said bell cranks, a series of jacks associated with said links for operating the same, and a dog movable concomitantly with said carriage for successively actuating each of said jacks.
21. The combination with a typewriting mechanism including a carriage and numeral keys, of a computing mechanism including a series of dial wheels and bars for operating said dial wheels, a series of hooks normally out of engagement with said bars, a plurality of linkages individual to each of said hooks for forcing said hooks separately into engagement with said bars, a bell crank for operating each of said linkages, a link connected to each of said bell cranks, a series of jacks for operating said links, a dog movable concomitantly with said carriage for

successively operating said jacks to successively force said hooks into engagement with said bars, a universal bar for operating all of said hooks, a universal bar for operating said first-mentioned universal bar, and means individual to said numeral keys for actuating said second-mentioned universal bar.

22. The combination with a typewriting mechanism, of a computing mechanism including a series of dial wheels, bars for operating said dial wheels, a series of hooks for moving said bars, springs for holding said hooks out of engagement with said bars, and typewriting mechanism controlled means for forcing said hooks into engagement with said bars.

23. The combination with a typewriting mechanism, of a computing mechanism including a series of dial wheels, bars for operating said dial wheels, a series of hooks for moving said bars, springs for holding said hooks out of engagement with said bars, typewriting mechanism controlled means for forcing said hooks into engagement with said bars, and means for manipulating said hooks to move said bars.

24. The combination with a typewriting mechanism including numeral keys and a carriage, of a computing mechanism including a series of dial wheels and bars individual to said dial wheels for operating the same, means universal to said keys and operated thereby, members individual to said bars for shifting the same, and carriage controlled means for concomitantly connecting certain of said members to said universal means and to said bars, whereby the operation of said keys will shift certain of said bars.

25. The combination with a typewriting mechanism including numeral keys and a carriage, of a computing mechanism including a series of dial wheels and bars individual to said dial wheels for operating the same, means universal to said keys and operated thereby, a member for each bar normally free therefrom, and carriage controlled means for concomitantly connecting said members to said universal means and their bars, whereby the operation of said keys will shift certain of said bars.

26. The combination with a typewriting mechanism having a carriage and numeral keys, of a computing mechanism having computing wheels and bars for rotating said computing wheels, jacks connectible to said bars individually, a dog carried by said carriage and normally in contact with one of said jacks when in register therewith for determining which of said bars shall be actuated, a normally-broken train of connections between said numeral keys and said bars, and means operated by said jacks individually for completing corresponding parts of said train of connections at said

bars, so as to enable said numeral keys to shift said bars.

27. The combination with a series of computing wheels, of a series of numeral keys, a series of rack bars for rotating said computing wheels, a direct train of connections between said numeral keys and said rack bars, said train of connections to all of said rack bars being normally interrupted at said rack bars, so as to hold said rack bars free from the sphere of influence of said numeral keys through the intermediary of said train of connections, and means for shifting individual parts of said train of connections individually into the sphere of control of said rack bars, so as to render said numeral keys capable of controlling individually the manipulation through said train of connections of one of said rack bars at a time.

28. The combination with a series of computing wheels, of a series of numeral keys, a series of rack bars for actuating said computing wheels, a train of connections universal to said numeral keys and individual to said rack bars, so as to enable the lifting of any one of said rack bars from any one of said numeral keys to effect the selection of a computing wheel to be rotated by its rack bar an extent corresponding to a numeral key struck, said train of connections being normally free and clear to said rack bars, so as to be incapable of actuating the same, a carriage, a lug on said carriage, a series of jacks to be operated *seriatim* by said lug during a movement of said carriage, and linkages connected individually to said jacks and arranged to actuate individual parts of said connections corresponding to the several rack bars, so as to bring said individual parts of said train of connections to a position capable of lifting the associated rack bars when any one of said numeral keys is actuated.

29. The combination with a series of numeral keys, of a series of computing wheels, a series of rack bars, one individual to each of said computing wheels, mechanism universally operable from said numeral keys, a series of interponents corresponding to said series of rack bars for actuating the same and normally in an ineffective position, said interponents being operable from said universal mechanism so as to be shifted by any of said numeral keys, a carriage, and carriage-controlled means for shifting said interponents individually to effective positions to enable them, after such shifting, to transmit movements from the actuated numeral keys to effect movements of opposite rack bars.

30. The combination with a carriage, of a series of numeral keys, a series of computing wheels, a series of rack bars for said computing wheels, a series of floating interponents for shifting said rack bars by en-

- gagement therewith, carriage-controlled means for controlling the effective and ineffective positions of said interponents, and numeral-key-actuated means for operating 5 said interponents after being shifted to an effective position.
31. The combination with a carriage, of a series of numeral keys, a series of computing wheels, a series of racks for operating 10 said computing wheels, a series of interponents, one individual to each of said racks for actuating said racks between effective and ineffective positions, means universal to said numeral keys for actuating said interponents, and carriage-controlled means for shifting said interponents individually into the sphere of movement of said universal means, so as to be actuated thereby to shift 15 individuals of said racks.
32. The combination with a series of numeral keys, a series of computing wheels, a series of rack bars, for actuating said computing wheels, a series of interponents, one individual to each of said rack bars for 20 shifting the same, said interponents normally out of operative positions, but shiftable individually to effective positions, a member universal to said numeral keys and universal to said interponents, any one of 25 said numeral keys being capable of actuating said universal member at any time, said universal member being normally incapable of actuating any of said interponents, and shifting means for bringing about a relative 30 co-operative movement between said universal member and said interponents to control the effectiveness of said universal member and thus said numeral keys to actuate said interponents after the movements 35 of the interponents to effective positions.
33. The combination with a series of type operating typewriter keys, of a universal member operated by said keys, a series of hooks normally inoperable by said universal 40 member, a competition member for each hook, a pivoted latch for each hook by which the universal member moves the hook, and thereby puts its computation member under the control of said keys, and means 45 for moving the hooks for bringing the latches to effective position.
34. The combination with a series of keys, of a universal member operated by said keys, a series of hooks normally inoperable by said 50 universal member, a pivoted latch for each hook by which the universal member moves the hook, a denomination selector, a transposition device, and means operated by said 55 denomination selector through said transposition device to move the hooks *seriatim* to effective position.
35. The combination with a series of keys, of a universal member moved by said keys, a series of hooks, a bar on which said hooks 60 are slidably pivoted, a spring latch for each 65 hook which is normally held in ineffective position, and means for swinging the hooks on said bar to bring the latches to effective position.
36. In a combined typewriting and computing machine, the combination with a series of jacks, of a carriage, numeral keys universal to said carriage, a denomination dog on said carriage effective on said jacks, a universal member operated by said keys, 70 and hooks operated by said keys through said universal member in an order determined by said denomination dog.
37. In a computing machine, the combination with a traveling carriage, and a 75 denomination dog, of a series of jacks, a pair of bell cranks operable by each of said jacks, a bar connected to each pair of said bell cranks, and computation column-determining hooks moved by said bars.
38. In a combined typewriting and computing machine, the combination with a 80 numeral key and a type operated thereby, of a stem on said key adapted to operate a linkage, a second stem on said key adapted to operate a universal member, and a bar moved by said universal member to effective position, so that the linkage may be effective 85 on the bar.
39. In a combined typewriting and computing machine, the combination with a numeral key and a type operated thereby, of a stem on said key adapted to operate a linkage, a second stem on said key adapted to operate a universal member, a bar moved 90 by said universal member to effective position, so that the linkage may be effective on the bar, a carriage controlled by said key, a dog on said carriage, and a bar-selecting 95 device controlled by said dog.
40. In a computing machine, the combination with a hook and a key-operated universal member for operating it, of a spring normally holding the hook so the universal member will be ineffective on it, a computation bar adapted to be moved by said hook, and a spring holding said hook, so that when the universal member is operative thereon, the hook will be in position to engage the computation bar.
41. In a computing machine, the combination with a rack bar and a hook for moving it to effective position, of a rod on which said hook is slidably pivoted, a spring normally holding said hook clear of said rack bar, a spring holding said hook so that it may be moved into effective position, a denomination-selecting device for moving the hook to effective position, and a key-operated universal bar for operating the effective hook.
42. In a combined typewriting and computing machine, the combination with a traveling carriage, and a denomination-selecting dog, of a transposition device oper- 125

ated by said dog, a series of bell crank levers forming part of said device, a vertical link for each pair of bell cranks, and a denomination-selecting projection on each link.

5 43. In a combined typewriting and computing machine, the combination with a traveling carriage, and a denomination-selecting dog, of a transposition device operated by said dog, a series of bell crank levers 10 forming part of said device, a vertical link for each pair of bell cranks, a denomination-selecting projection on each link, rack bars normally in ineffective position, and means for moving said rack bars to effective 15 position operable by said projections.

44. In a combined typewriting and computing machine, the combination with a series of denomination-selecting hooks, of a universal bar movable along said hooks, a 20 latch on each hook by which said universal bar may move it, a spring normally holding each latch in effective position, and a pivot for each latch on which it may swing to permit independent motion of the hook and 25 the universal bar.

45. The combination with a carriage, a denomination selector, and a series of numeral keys, of a computing mechanism including jacks on which said selector is effective, a series of computing wheels and actuating mechanism for said computing wheels, a pin bar for each wheel forming part of said actuating mechanism, a direct train of connections between said numeral keys and 30 said computing mechanism actuated by said numeral keys to control the particular wheel to receive a number corresponding to the numeral key actuated, means supporting said pin bars beyond the control of said 35 keys, whereby said train of connections is normally interrupted at said wheel actuating mechanism, and means, including a series of interponents normally inoperative but shiftable individually to effective positions 40 by the keys, whereby each numeral key acts through the shifted interponents to lift its pin bar clear of its normal support and simultaneously depresses its pin thereon against the support of the key.

50 46. The combination with a carriage and a denomination selector thereon, of a series of numeral keys, a computing mechanism including jacks on which said selector is normally effective, a series of computing wheels 55 and a series of rack bars for driving said wheels to run up numbers on said computing wheels, a pin for each numeral key on each of said bars, a direct train of connections between said numeral keys and said 60 computing mechanism actuated by said numeral keys to control the particular wheel to receive a number corresponding to the numeral key actuated, a support for each rack bar normally holding its pins beyond 65 the numeral keys, whereby said train of con-

nections is normally interrupted at said rack bars, and means whereby each numeral key lifts its bar to bring its pins within range of the key and sets its pin thereon against the support of the key.

70 47. The combination with a carriage and a denomination selector thereon, of a series of numeral keys, a computing mechanism including jacks on which said selector is normally effective, a series of computing 75 wheels and a series of rack bars for driving said wheels to run up numbers on said computing wheels, a pin for each numeral key on each of said bars, a direct train of connections between said numeral keys and said 80 computing mechanism actuated by said numeral keys to control the particular wheel to receive a number corresponding to the numeral key actuated, a support for each bar normally holding its pins beyond the 85 numeral keys, whereby said train of connections is normally interrupted at said rack bars, means whereby each numeral key lifts its bar to bring its pins within range of the key and sets its pin thereon against the support of the key, and carriage-controlled 90 means for completing the train of connections at said rack bars.

48. The combination with a carriage, a denomination selector thereon, and a series 95 of computing wheels, of actuating mechanism including rack bars for said computing wheels, indexing mechanism including pins on said rack bars for determining the extent of actuation of said computing wheels, decimal column-selecting mechanism for lifting said rack bars to render said indexing mechanism settable, said column-selecting mechanism including jacks on which said selector 100 is normally effective and being normally interrupted at said actuating mechanism so as to be incapable of actuating the parts of said actuating mechanism to enable a computing indexing, means for shifting said column-selecting mechanism to a position 105 effective to actuate the parts of said actuating mechanism, and numeral-key-actuated means for concomitantly setting said pins and lifting the rack bars of said actuating mechanism to effect the selection of a computing wheel to be rotated and the extent of 110 its rotation.

49. The combination with a carriage, a denomination selector, and a series of numeral keys, of a series of computing wheels, actuating mechanism for said computing wheels including rack bars, indexing mechanism including pins on said bars for determining the extent of actuation of said computing wheels, decimal column-selecting mechanism for shifting said rack bars to render said indexing mechanism effective, said column-selecting mechanism including jacks on which said selector is normally 120 effective and being normally interrupted at 125 130

5. said pins, so as to be incapable of actuating the pins of said actuating mechanism to enable a computing indexing, a carriage, carriage-controlled means for shifting the column-selecting mechanism to a position effective to enable the indexing of said actuating mechanism, and numeral-key-controlled means for concomitantly actuating said indexing mechanism and said column-selecting mechanism to determine the computing wheel to be rotated and the extent of its rotation. 70
10. 50. The combination with a series of computing wheels, of a series of numeral keys, a series of rack bars for rotating said computing wheels, settable pins on said bars, a direct train of connections between said numeral keys and said rack bars including hooks for raising said bars, said train of 75 connections to all of said rack bars being normally interrupted at the pins on said rack bars, so as to hold said rack bars free from the sphere of influence of said numeral keys through the intermediary of said train of connections, and means for bringing about a relative movement between said rack bars and said hooks so as to lift certain of said rack bars to set pins on the lifted bars from said numeral keys. 80
15. 51. The combination with numeral keys and pins settable thereby, of bars on which said pins are settable, a carriage for selecting said bars, an interponent for each bar for so selecting the bar, and means operated by the numeral keys for first setting any interponent and then moving any bar by said interponent to move its pin to position where the key will be effective on it. 85
20. 52. The combination with a numeral key and a linkage operable thereby, of a rock shaft by which said key operates said linkage, a bar comprising a device normally inoperative by said linkage, means moved by said key to shift said bar to make said device operable by said linkage, a hook forming part of said means, and a denomination selector for selecting the hook. 90
25. 53. The combination with a series of bars, each having a series of settable devices thereon, of a series of keys for setting said devices, a universal bar operated by said keys, a series of normally inoperative interponents individually shiftable by the numeral keys to operative positions and then 95 operable by said numeral keys for moving said first-named bars to enable the keys to set said devices, jacks for selecting said members, and a traveling carriage normally effective on said members for determining on which bar said keys may be so effective. 100
30. 54. In a computing machine, the combination with a series of numeral keys, of a pawl connected to each of said numeral keys, a universal bar operated by said pawls, normally-ineffective computation bars, pivoted 105
35. hooks for making said computation bars effective, and a traveling carriage adapted to make said hooks simultaneously effective on said bars and put them under the control of said universal bar. 110
40. 55. In a computing machine, the combination with a hook, of a pivot on which it slides and turns, a bar adapted to be caught by said hook, and a pendant-lifter pivoted to said hook and adapted to swing to effective position whenever said hook is made effective on its bar. 115
45. 56. In a computing machine, the combination with a hook and a computation bar, of a universal bar, a catch pivoted to said hook, and adapted to pass said universal bar in one direction, and to be caught by said hook in the opposite direction, and means for swinging said hook to simultaneously engage its computation bar and to 120 carry its hook to effective position adjacent said universal bar. 125
50. 57. In a computing machine, the combination with a hook and a computation bar, of a universal bar, a catch pivoted to said hook, and adapted to pass said universal bar in one direction, and to be caught by said hook in the opposite direction, means for swinging said hook to simultaneously engage its computation bar and to 130 carry its hook to effective position adjacent said universal bar. 135
55. 58. In a computing machine, the combination with a numeral key, bars and pins thereon, of means whereby said numeral key is adapted to both support a bar and shift a pin on said bar when so supported, a traveling carriage, jacks for determining on which bar said key is effective, and a selector on said carriage and normally effective on said jacks. 140
60. 59. In a computing machine, the combination with a series of type operating typewriter keys, of a universal bar, a series of hooks in front of said bar, a computation member for each hook and in front of its hook, a pivoted catch on each hook, and means for selectively moving said hooks forwardly to swing their catches rearwardly over said universal bar, so that any hook is simultaneously put under the control of said bar and made effective on its computation member. 145
65. 60. In a computing machine, the combination with numeral keys and a traveling carriage, of a denomination selector forming part of said carriage, a series of jacks, denominational bars normally disconnected from said jacks, and means operated by said numeral keys for connecting said jacks to said bars. 150
70. 61. In a computing machine, the combination with a series of type operating typewriter keys, of a universal bar, a series of hooks in front of said bar, a computation member for each hook and in front of its hook, a pivoted catch on each hook, and means for selectively moving said hooks forwardly to swing their catches rearwardly over said universal bar, so that any hook is simultaneously put under the control of said bar and made effective on its computation member. 155

nation with numeral keys and a traveling carriage, of a denomination selector forming part of said carriage, a series of jacks, denominational bars normally disconnected from said jacks, means operated by said numeral keys for connecting said jacks to said bars, a hook for each key, and a uni-

versal bar operated by said numeral keys for so connecting said jacks to said bars.
